UNITED STATES PATENT OFFICE.

REUBEN HALEY, OF BEAVER, PENNSYLVANIA.

DESIGN FOR AN AUTOMOBILE HEADLIGHT LENS.

61,136.

Specification for Design.

Patented June 27, 1922.

Application filed March 13, 1918. Serial No. 222,249. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for an Automobile Headlight Lens, of which the following is a specification, reference being had to the accompanying drawings, forming a part thereof, wherein—

Figure 1 is a front elevation; Fig. 2 is a sectional elevation taken on line 2—2 of

Fig. 1, and Fig. 3 is a view in section taken on line 3—3 of Fig. 1 looking in the direction of the arrow of an automobile headlight lens.

I claim:

The ornamental design for an automobile headlight lens, substantially as shown.

REUBEN HALEY.
